UNITED STATES PATENT OFFICE.

JOSEPH L. WELSHANS, OF CHICAGO, ILLINOIS.

VACUUM HEATING SYSTEM.

No. 905,037.

Specification of Letters Patent.

Patented Nov. 24, 1908.

Application filed May 1, 1908. Serial No. 430,350.

To all whom it may concern:

Be it known that I, JOSEPH L. WELSHANS, a citizen of the United States, and a resident of Chicago, in the county of Cook, in the State of Illinois, have invented certain new and useful Improvements in Vacuum Heating Systems; and I do hereby declare that the following description of my said invention, taken in connection with the accompanying sheet of drawings, forms a full, clear, and exact specification, which will enable others skilled in the art to which it appertains to make and use the same.

This invention has general reference to improvements in vacuum-heating systems; and it consists, essentially, in the novel and peculiar combination of parts and details of construction, as hereinafter first fully set forth and described, and then pointed out in the claims.

The object of this invention is the production and installation of an economic, serviceable, simple, and efficient vacuum-heating system that shall require but very little attention by being as nearly automatic, as a heating system can be made.

In the drawings already referred to, which serve to illustrate this invention, Figure 1 is a diagrammatic view of a complete vacuum-heating system, some of the parts of which are not drawn to correct scale, but rather enlarged to more clearly illustrate the same. Fig. 2 is a sectional elevation of a modified form of water-seal employed in this heating-system.

A in the drawings, represents a water-heater or steam-generator of any approved form or construction, and fitted with all the necessary appurtenants, such as water-column 2, with its gage-cocks 3, and glass water-gage 4; damper-regulator 5, pressure and vacuum-gage 6, and such other appliances, (not shown,) which are now considered essential to a perfect steam generator. This steam generator A is connected with the water-distributing system 7, by a branch-pipe 8, having a stop-valve 9, so that the said generator may be charged with its required quantum of water and, at any subsequent time a deficiency therein supplied by opening the stop-valve 9 in an obvious manner.

10 are a series of radiators of usual construction suitably disposed within a building, and all connected with a supply-pipe 11, 55 which pipe leads from the generator A to

these various radiators 10, and also forms the return for any water of condensation that may accumulate in the heating system.

12 is a tank or reservoir. It connects with the main supply-pipe of the heating system 60 by means of a branch 13, having a shut-off valve 14, so that any accumulation of water in this tank may be drawn therefrom by opening said shut-off 14, and then returned to the generator A by the main 11.

15 is a system of air pipes, connecting the various radiators 10, with the tank 12 and with said radiators 10 through air-valves, 16, of approved construction.

B is a combined water-motor and air-pump, the lower section, 18 of which being the water-motor, and the upper section, 19 the air-exhauster, the latter being connected with the tank 12 by the pipe, 20, entering the tank either from the bottom and reaching near its top, or connecting directly with the top of the tank 12, the object being to prevent water (if present,) being drawn from said tank into the air-exhauster 19; the exhausted air being discharged into the atmosphere at the discharge nozzle 21.

C is a by-pass for the water-distributing system 7, and consists of a system of pipes 23, leading from the main in front of the water-motor 18 back to the main in the rear 85 of the water-motor; there being inserted into this system a pressure-regulator, 24, of approved construction, and a series of shut-off valves 25, 26; the former serving the water-main, and the latter the by-pass.

27 is a water faucet and 28 a sink, or other apparatus to which water is conducted for household use, such as, water-closets, bath-tubs, lavatories, &c., and of which there may be as many as found necessary or desirable; all of which being connected with the water-main 7 in the usual and approved manner.

Having thus fully described the essential parts entering into this system of heating, I shall now proceed to describe its operation.

The water-motor 18, which I prefer to use, operates intermittently, that is to say, when water is drawn at any of the means for withdrawing water from the water-distributing system 27 within the building, the same has to pass through the pump-cylinder and the pressure exerted upon the water-piston forces the latter upward and when at its highest point, reverses and returns to its

normal position by mechanism within said pump, which mechanism, being well-known, is not shown in detail in the drawings, the operation of the water-motor continuing as long as water is drawn from any of the said faucets or discharges 27. The action of this water-motor 18 actuates the exhauster 19, which is an air-pump of well-known construction, and which is connected with the tank 12 and through it with the system of air-pipes 15 and radiators 10, and which exhauster draws from the entire heating-system the inclosed air.

It is a well-known fact that water boils *in vacuo*, or in a partial vacuum at a lower temperature than at atmospheric pressure which fact is utilized in all vacuum-heating systems and, is also the means employed in my present invention. When as high a vacuum has been reached within this heating-system, as is possible by the mechanical devices employed, it requires only that the same be maintained as long as heat is required and, therefore, the air-exhauster needs not operate continuously or for any very great length of time; and since the water-motor B would operate as long, or as often as, water is drawn from the water-supply, I have introduced the by-pass system into the water-distributing system, so that, by adjusting the pressure-regulator 24 in the usual manner, it will open, the current of water in the main, instead of passing through the water-motor, will pass through the by-pass system until the vacuum in the air and heating system falls below a predetermined point when the water-motor will again begin to operate and the water pass through the direct main until the required vacuum is obtained.

I have introduced the stop-valves 25 into the water system in order to provide for means to shut off the water by the stop-valves 25, should it be necessary at any time to remove the water motor from the system for repairs or other purposes, and the stop-valves 26, to enable repairs, etc., being made to the pressure-regulator 24, thereby permitting the water-supply being uninterruptedly used regardless of such repairs as described being made. This by-pass system is an essential element in the present system of heating, resulting in a saving of power, reduction of wear of parts, and preventing interruption of the water supply, and other obvious advantages. I have introduced into this system of heating *in vacuo*, the tank 12 for the purpose of furnishing an auxiliary reservoir from which the air is exhausted and thereby to increase the space *in vacuo*, beyond that of the steam-generator, the piping, and the radiators, so that should the air-exhauster remain inoperative for any length of time, owing to the fact that no water is drawn from the water-main or fau-

cets, &c., the heating system will not be seriously affected by such temporary stoppage of the air-exhauster.

In order to prevent any possibility of the steam in the generator A from escaping from the boiler to the return pipe and thereby destroying the vacuum and preventing or retarding the return of the water of condensation, I provide a deep-water seal D, consisting of an outer casing 30, having a reducing socket 31, at its lower end a plug 32, by the removal of which access may be had to the interior of said deep-water seal, and in its upper end a further reducer 33, to which connects the main or steam pipe 11, already referred to. This pipe 11 reaches so near the bottom of the outer casing 30 so that any accumulation of water of condensation may collect therein and overflow through the branch-pipe 34 and return to the steam-generator A by the pipe 35. This water-seal is an essential feature of this system of vacuum-heating since it prevents steam from entering the return-pipe, as heretofore stated. Instead of this peculiarly-constructed water-seal I may use other approved seals for sealing the discharge-end of the steam-pipe system without changing the nature of my invention, and in Fig. 2, I have shown a modification of such a system of sealing the main-steam discharge, where instead of the outer casing 30 I employ a return pipe 36 and return bends 38 and 39, connecting the return bend 38 with the steam-space in the steam-generator A at any suitable place. In this system the water of condensation will fill the pipe 36 to return-bend 38, and overflow into pipe 35 to return to the steam generator the same as shown in the preferred form illustrated in Fig. 1.

Instead of using on the radiators the air-valves 16, as shown on two of the radiators, I may use a thermostatic trap 41, shown on the radiator at the extreme right of the drawings.

When such a thermostatic trap is being used I connect the same with the air-supply, the same as shown in connection with the air valves, but in this case I also connect the air-return-pipe with the return-pipe 11 by a short branch 42, so as to conduct the water of condensation from the radiators 10 back to the boiler through the water-seal and thereby prevent water from being drawn into the exhauster.

Having thus fully described my invention I claim as new and desire to secure to me by Letters Patent of the United States—

1. The combination of a steam heating system, comprising a steam generator, a radiating system and an air-exhauster, a water distributing system, including means for withdrawing water therefrom, said water distributing system being in communication with said generator, a water motor for said

air-exhauster, arranged to be operated when water is withdrawn from the water-distributing system, a by-pass around said water motor, and means for directing the water through either said motor or said by-pass.

2. The combination of a steam - heating system comprising a steam generator, a radiating system and an air-exhauster, a water distributing system, including means for drawing water therefrom, said water distributing system being in communication with said generator, a water motor for said air-exhauster arranged to be operated when

water is withdrawn from the water-distributing system, a by-pass around said water motor, and a pressure regulator in said by-pass whereby the water supply is directed through either said motor or said by-pass.

In testimony that I claim the foregoing as my invention I have hereunto set my hand in the presence of two subscribing witnesses.

JOSEPH L. WELSHANS.
